ANTENNA

Application filed February 18, 1930, Serial No. 429,282, and in Germany February 19, 1929.

It is known that in order to eliminate disturbances caused by the "fading" effect, circularly or elliptically polarized waves are used for the transmission of signals. The 5 present invention has as an object the provision of an aerial arrangement which will allow the transmission of circularly polarized waves and at the same time will have a very marked directional effect.

10 In order to transmit circularly polarized waves two aerials are placed at right angles to each other and excited by means of currents with a relative temporal phase displacement of 90°. Although the two aerials carry co- 15 phasal currents they are arranged spacially in such a manner that the required phase displacement is obtained as a result of the difference in the length of path travelled by the radiated waves. Either circularly polarized or elliptically polarized fields may be 20 obtained by suitable spacing of the vertical and horizontal antennæ and by suitable phasing of the currents therein. Elliptical polarization may also occur when the currents 25 in the horizontal and vertical antennæ are of different magnitude.

Further in order to obtain a distinct directive effect it is a further object to employ the beam-aerial principle which consists in placing 30 a system of transmitters or emitters in one plane together with the right angled antennæ. The aerial layout according to this invention comprises two antenna systems, one consisting of a number of horizontal linear 35 aerials arranged in one plane and the other consisting of corresponding vertical linear aerials. These two antenna systems are suitably connected by means of power lines to the radio frequency transmitter in such a 40 manner as to secure the required phase displacement for the emitted vertical or horizontal fields. The proper phase displacement is obtained in the familiar manner by including in the circuit suitable tuning devices. In addition, it is desirable to provide 45 these antenna systems with reflector arrangements.

One antenna layout in accordance with the invention is illustrated on the attached figure. 50 Referring thereto *e* represents the power

lines supplying the various horizontal transmitters and *E*—the power lines which feed the vertical aerials. The separate horizontal and vertical aerials are marked *a* and *b* respectively. *A*₁ and *A*₂ as well as *C*₁ and *C*₂ 55 denote adjusting transformers for the vertical and horizontal beams and *t* the radio frequency combination transformers for the combined vertical and horizontal systems. *A'*₁ is the adjusting transformer for the 60 vertical beam of the reflector aerial, which is analogous to the transmitting antenna system but placed in the rear thereof.

An aerial layout in accordance with this 65 invention may obviously be applied for receiving purposes as well.

I claim as my invention:

1. An aerial layout, particularly for short wave operation, employing two antenna systems, one comprising of a number of vertical linear aerials arranged one above the other in one plane, the other comprising a number of horizontal linear aerials arranged in a plane parallel to and spaced from the first, 70 each of the two antenna systems being connected by means of separate transmission lines to common high frequency apparatus, and phase adjustment apparatus associated with each of said separate transmission lines. 75
2. An aerial layout according to claim 1, 80 wherein a reflector, similar to said antenna systems, is provided for the aerial layout.

OMMO SCHMIDT.
